UNITED STATES PATENT OFFICE

2,490,464

FLOOR FURNACE CLOSELY CONFINED IN A
PIT AND HAVING AN ACCESS DOOR

Ausphrey M. Odom, Memphis, Tenn.

Application July 12, 1946, Serial No. 683,022

1 Claim. (Cl. 126—116)

1

This invention relates to an access door for a floor furnace and has for its primary object to facilitate the connection of the furnace to a fuel supply pipe and to the flue through which the products of combustion are vented.

Another object of the invention is to permit the use of floor furnaces in pits of minimum dimensions.

The above and other objects may be attained by employing this invention which embodies among its features an opening through one side of the shell of the furnace through which access may be had to the fuel supply pipe and the flue connection to the furnace, and a door applicable from the interior of the shell to close the opening.

Other features include detachable fasteners operable from the interior of the shell to hold the door in a position to close the opening in the shell of the furnace.

In the drawings,

Figure 1 is a sectional view through a pit showing my improved furnace installed therein,

Figure 2 is a horizontal sectional view taken substantially along the line 2—2 of Figure 1,

Figure 3 is a sectional view taken substantially along the line 3—3 of Figure 2, and

Figure 4 is a sectional view taken substantially along the line 4—4 of Figure 2.

Referring to the drawings in detail, the floor 10 of a building structure is equipped with a pit 11 to which a cold air duct 12 leads from the exterior of the building in a conventional manner. A conventional floor furnace of the type sold under the trade-mark "Coleman" designated generally 13 is shown as entering the pit and is supplied through pipes 14 with fluid fuel in a conventional manner while the products of combustion are discharged to a flue through a conventional flue pipe 15 connected to the furnace 13. The structure so far recited is that commonly employed except that the pit 11 in prior constructions must be made of such large dimensions as to accommodate the workmen between the wall of the furnace and the wall of the pit in order to make the necessary connection to the fuel pipe 14 and the flue.

In order to permit the furnace to be employed in a pit of smaller dimensions I form in the outer shell 16 of the furnace an access door opening 17 which is adapted to be closed by a removable door panel 18 held to the casing or shell 16 of the furnace by means of suitable fasteners 19 which may be manipulated from the interior of the furnace. It is to be noted that the door 18 overlaps the marginal edges of the opening 17 on the inner face of the wall of the shell as clearly illustrated in Figure 2. A suitable gas-tight gasket 20 is interposed between the overlapping

2

edge of the door 18 and the adjacent portion of the shell or casing 16.

In installing the furnace the fuel pipe 14 is equipped with a union 21 carried on a nipple 22 which is of such a length as to permit access to the union 21 through the opening 17. This union is in turn, connected to the fuel pipe 23 of the furnace after the furnace has been lowered into place and before the panel or door 18 is secured in position to close the opening 17. Likewise, the flue coupling 24 of the furnace is connected to the pipe 15 through the opening 17 after which the door 18 is secured over the opening from the interior of the furnace in order to effectively enclose the furnace. From the foregoing it will be obvious that a pit 11 need be only of a dimension sufficient to accommodate the furnace and the piping, as access may be had to effect the coupling of the furnace to the piping through the opening 17.

While in the foregoing there has been shown and described the preferred embodiment of this invention it is to be understood that minor changes in the details of construction, combination and arrangement of parts may be resorted to without departing from the spirit and scope of the invention as claimed.

I claim as my invention:

In a furnace construction including a pit below the level of the floor of a building structure; a floor furnace, said furnace including a heating unit, a shell surrounding the bottom and sides of the heating unit, the walls of the pit closely surrounding the shell, fuel pipe and flue connections connected to the heating unit and disposed outside of the shell adjacent one side thereof, fuel pipe and flue connections in the pit adjacent the side of the shell adjacent which the first mentioned fuel pipe and flue connections are disposed, said shell having an access opening in the side adjacent the fuel pipe and flue connections through which the fuel pipe and flue connections are accessible, and a door detachably connected to the inside of the shell and accessible through the top of the furnace for closing the access opening, the space between the shell and the walls of the pit being inaccessible except through the access opening.

AUSPHREY M. ODOM.
